UNITED STATES PATENT OFFICE.

LODGE W. WEGENKA, OF SOUTH BEND, INDIANA.

AUTOMOBILE DOOR-BUMPER.

1,127,329.

Specification of Letters Patent.

Patented Feb. 2, 1915.

Application filed June 15, 1914. Serial No. 845,219.

To all whom it may concern:

Be it known that I, LODGE W. WEGENKA, a citizen of the United States, residing at South Bend, in the county of St. Joseph 5 and State of Indiana, have invented certain new and useful Improvements in Automobile Door-Bumpers; and I do hereby declare the following to be a full, clear, and exact description of the invention, such as 10 will enable others skilled in the art to which it appertains to make and use the same.

My invention relates to new and useful improvements in automobile doors and more particularly to metallic bumpers therefor 15 and resides in the provision of such a device that may be readily attached to the door jamb and will operate in a reliable manner to cushion the impact of closing the door so that injury thereto or to the latch is 20 prevented.

An object of importance is to provide a metallic spring bumper that is of simple construction, capable of being readily attached and detached, is durable and not apt 25 to become broken or deranged as is the case with the ordinary bumper ordinarily used and is inexpensive to manufacture.

The above and additional objects are accomplished by such means as are illustrated 30 in the accompanying drawings, described in the following specification and then more particularly pointed out as claimed.

With reference to the drawings, wherein I have illustrated the preferred embodiment 35 of my invention as it is reduced to practice, and throughout the several views of which similar reference numerals designate corresponding parts: Figure 1 is a front elevation of my improved spring bumper, Fig. 2 is a side elevation showing the bumper attached to the jamb of a door, Fig. 3 is a detail perspective view of the spring bumper plate, and Fig. 4 is a detail perspective view of the bumper holding 40 plate.

Referring to the drawings by characters of reference; A designates the jamb of an automobile door to which my improved bumper is to be attached, in such position 45 as will correspond with that in which the ordinary bumpers are usually placed.

Mounted upon one angular face portion of the door jamb A is a rectangular body or spring holding plate 1, that is formed of 50 some suitable preferably sheet metal, that is bent centrally of its ends to provide an

inverted V-shaped transverse projection 2 for a purpose to be later more fully described.

Openings 3 are formed adjacent to the 60 ends of the plate 1 and receive screws 4 or other suitable fastening elements that are turned or inserted in the jamb A to secure the plate, said plate being secured in a vertical position so that the V-shaped projection 2 is extended outwardly from the door jamb. 65

A rectangular tongue 5 is formed integral with one end, preferably the lower end of the plate 1 on one side thereof and is bent to lie over the adjacent end of the plate in spaced parallel relation thereto and provided with an opening 6 therein which alines with the opening 3 in the adjacent end through which one of the screws or other suitable fastening element 4 is inserted. This plate 1 and corresponding parts is made relatively flat and one side edge and the free end edge of the tongue are disposed flush with the corresponding 75 edges of the adjacent end of the plate 1. 80

Mounted upon the spring holding plate 1 is a spring bumper plate designated 7 as an entirety that is preferably rectangular and formed of some suitable spring metal. This 85 plate 7 is approximately the same length and width as the plate 1 and is bent to provide an approximately U-shaped door engaging projection 8 that consists of outwardly and inwardly inclined side portions 90 9 and a flat portion 10 which joins the portions 9 with each other which is formed integral therewith. The door engaging portion 8 is centrally of the ends of the plate 7 and in such manner that the V-shaped projection 2 is received therein and normally spaced therefrom as clearly shown in Fig. 2 in the drawings. 95

A longitudinal slot 11 is formed in the lower end of the plate 7 and slidably receives the fastening element 4 so that the plate is permitted to move relative to the plate 1. An opening 12 is formed in the other end of the plate 7 and receives the other fastening element 4 which is inserted 100 through the opening 3 in the corresponding end of the plate 1. The end of the plate 7 that is provided with the longitudinal slot 11 is positioned between the plate 1 and tongue 5 so as to be securely and slidably held in position. The slot 11 alines with the openings 3 and 6 so that the fastening ele- 105 110

ments 4 may be inserted therethrough and into the door jamb.

In practice the device is secured in a vertical position as illustrated clearly in Fig. 5 2 in the drawings upon the door jamb A and in such a position that upon the closing of the door, not shown, the door engaging portion 8 will first engage the door and its flat portion 10 and give owing to the 10 spring action of the plate 7. The give is permitted through the medium of the longitudinal slot 11 which allows the plate to slide relative to the plate 1.

It will be readily seen that I have provided a simple, inexpensive and effective door bumper that is extremely durable and will provide the desired cushioning action in a reliable manner. Should the door, not shown, be closed with great force and the 20 spring plate 8 give a great deal, the V-shaped projection 2 on the plate 1 will act as a stop and in engaging the inner face of the flattened portion 10 of the door engaging member or portion 8.

25 In practice, I have found that the form of my invention, illustrated in the drawings and referred to in the above description, as the preferred embodiment, is the most efficient and practical; yet realizing 30 that the conditions concurrent with the adoption of my device will necessarily vary, I desire to emphasize the fact that various minor changes in details of construction, proportion and arrangement of parts may

be resorted to, when required without sacrificing any of the advantages of my invention, as set forth.

What is claimed is:-

A bumper of the character described consisting of a plate to be secured upon a door jamb and having an overlying tongue formed integral with one end thereof and being apertured, said plate being apertured in the end adjacent to the tongue and having its aperture alined with the aperture in the tongue, an outwardly extending approximately V-shaped projection formed intermediate of the ends of the plate, a spring plate having an outwardly extending projection formed intermediate its ends by bending said plate outwardly, slidable upon the first plate and having a longitudinal slot in one end registering with the opening in the tongue and first named plate and a bolt inserted through the alined openings and slots, a fastening element inserted through the ends of the plates farthest removed from the slot and tongues thereon to secure the plates to each other and to a door jamb and said V-shaped projection being normally spaced from said outwardly extended portion.

In testimony whereof I affix my signature in presence of two witnesses.

LODGE W. WEGENKA.
